UNITED STATES PATENT OFFICE.

FRANCIS MEAD, OF CHICAGO, ILLINOIS.

RESILIENT WHEEL.

1,195,379.

Specification of Letters Patent. Patented Aug. 22, 1916.

Application filed October 7, 1915. Serial No. 54,478.

To all whom it may concern:

Be it known that I, FRANCIS MEAD, citizen of the United States, residing at Chicago, in the county of Cook and State of Illinois, have invented certain new and useful Improvements in Resilient Wheels; and I do hereby declare the following to be a full, clear, and exact description of the invention, such as will enable others skilled in the art to which it appertains to make and use the same.

My invention relates to resilient wheels for vehicles and more particularly to the class of such wheels having resilient cushionings interposed between relatively movable inner and outer rims or felloes.

One general object of my invention is that of providing a construction affording great resiliency with relatively little wear on the cushioning elements, and one in which the stresses due to a relative circumferential movement of the rims are distributed through the whole of each cushioning element.

Another object is to provide simple and effective cushioning means to care for side strains upon the wheel (such as those due to skidding), also to prevent such side strains from unduly wearing the cushioning elements and from causing objectionable noises.

Still another object is to provide means for preventing the entrance of dirt, rain, snow, etc., into the space in which the cushioning elements are housed, and to prevent these mud-excluding means from interfering with the relative radial, lateral and circumferential motion of the wheel rims.

A further object is to provide cushioning elements suitable for use in a wheel construction of the class described, which will offer an unusual elasticity and of such shape as to afford substantially a maximum of elasticity when fitted between the rims of the wheel.

Still further objects will appear from the following specification and from the accompanying drawings in which—

Figure 1 is an elevation of a wheel embodying my invention, with portions cut away to disclose a part of the interior construction. Fig. 2 is an enlarged transverse section through the rim of the wheel and a part of one of the spokes. Fig. 3 is a fragmentary similar section with the wheel under side strain. Fig. 4 is a fragmentary section of the wheel taken along the line 4—4 of Fig. 2. Figs. 5 and 6 are fragmentary views

showing two different arrangements of the thrust partitions engaging the ends of the cushioning elements. Fig. 7 is a fragmentary view showing one of the cushioning elements at the top of a lightly loaded wheel when the latter is standing still. Fig. 8 is a similar view taken when the wheel is in motion. Fig. 9 is a similar view of one of the lower cushioning elements. Fig. 10 is an elevation of a cushioning element when loose. Fig. 11 is a view of the same as it appears when bent into position.

While my invention may be applied with substantially equal facility to wheels of widely varying materials and constructions, it is particularly applicable to wheels having wooden spokes and carrying treads upon demountable rims, and is shown in a corresponding embodiment in some of the drawings. Thus, in Fig. 1, the hub of the wheel supports spokes 2 carrying an inner rim or felly 3, which rim is banded by a steel ring 4. Encircling the said rim 3 at some distance therefrom, and preferably wider than the inner rim 3, is an outer rim 5 which carries tires 6 fitted into demountable rim elements 16 of any desired types. Secured to opposite sides of the outer rim 5 (preferably by the same bolts 17 which secure the demountable tire members in place) are side flanges 7, each of which projects radially inward of the wheel beyond the inner rim 3, and which flanges have offset portions 8 bearing against each other and bolted to each other between the spokes 2 of the wheel (as shown in Fig. 4). Adjacent to each spoke, each of these side flanges is equipped with a recessed formation 9, the opposed formations upon the two flanges combining to form short tubes loosely housing portions of the spokes. Clamped to each of these tubes and also suitably secured to the adjacent spoke (as for example, by being clamped over a spacing tube 19 as in Fig. 2) is a flexible tube or cuff 10, which flexible element forms a closure for the opening between the spoke and the adjacent tube 9.

Secured alternately to the inner and outer rims in circumferential succession, and projecting radially of the wheel for part of the distance between the said rims are thrust partitions 11 and 12, the former being preferably welded to the steel ring 4, which ring also carries a centrally disposed and radially projecting annular partition 13 between the rims in the space bounded laterally by the

center partition ring 13 and one of the side flanges, and bounded at its ends by the radial thrust partitions 11 and 12, are cushioning elements 14 made of rubber or other resilient material. Each of the cushions 14 is preferably wider than the width of the ring 4 laterally of the center partition 13, and normally engages both said partition 13 and one of the side flanges 7, thereby keeping this flange spaced laterally from the inner rim 3. Should the wheel be subjected to a side strain tending to move the inner rim laterally with respect to the outer rim (as in case the wheel skids on a wet street), one of the two cushions disposed at opposite sides of the center partition 13 will be compressed as in Fig. 3, during the relative lateral movement of the rims. To prevent the other cushion from being simultaneously slid in the same direction in which the first named cushion was compressed, I preferably interlock it with a formation disposed circumferentially of the wheel upon the ring 4, such as a raised ring 15. I also preferably make each cushion 14 of such a resiliency that the maximum lateral compression due to normally encountered side strains upon the wheel will not suffice to bring the adjacent side flange into contact with the inner rim, thus avoiding a noisy slamming or pounding action when the wheel is in service.

While the cushions 14 may vary greatly in design and material, I preferably so shape them that they will offer substantially equal resiliency in all directions when fitted into a loose wheel, that is to say, a wheel carrying no load. To accomplish this with a minimum of delay in the fitting and with no waste of the expensive rubber, I preferably mold each cushion in a substantially prismatic form having one longitudinal face sufficiently longer than the opposite face to compensate for the difference in the lengths of the arcs in which these faces are normally curved. Thus, in flexing the cushion of Fig. 10 into the active shape of Fig. 11, the upper face will be stretched and the lower face compressed. Normally, with a high grade of rubber or the like, the amount of compression at the inner surface should equal the expansion at the outer edge, thus tending to leave the ends of the cushioning block radial if these ends were originally at right angles to the said upper and lower faces. However, owing to the difference in radius, the length of the lower arc of Fig. 11 corresponding to radial ends will be less than that of the upper arc, hence an additional length of the upper face will be required to afford the desired disposition of the ends. I therefore preferably mold each cushioning block with a suitably enlarged outer face as shown in Fig. 10, thereby enabling this cushion to exactly fill the space for the same without disproportionate

strains upon any portion of it, and thereby also enabling each cushion to offer a substantially equal resiliency in all directions. I also preferably provide each of these cushions with a plurality of lateral recesses at each side, which recesses reduce the amount of material along the axis of the cushion and hence permit the cushion more easily to adapt itself to the changes in size and form demanded by the action upon the cushion when at different points in the travel of the wheel. For example, with the wheel standing still, the inner rim will normally compress the lower cushions to move the axis of this rim below the axis of the outer rim, thus increasing the distance between the uppermost portions of the two rings. Consequently, the resiliency of the cushioning block in tending to straighten this block may cause the latter to engage the rims only for a slight distance near each of the respective abutments 11 and 12, as in Fig. 7. However, if the wheel is set in motion, the tendency of one rim to lag behind the other will cause the said abutments to move toward each other, thereby compressing the cushion circumferentially and hence expanding the same radially of the wheel as in Fig. 8, the result being that both the inner and outer faces of the cushion offer a greatly extended amount of surfaces in contact with the adjacent rims. At the same time, the cushions at the bottom of the wheel will be subject both to the radial compression due to the lowering of the axis of the inner rim, and to the circumferential compression due to the lagging of one rim behind the other, thus forcing the entire inner and outer surfaces into contact with the rim members of the wheel. Consequently, since the cushions subject to the greater driving strains automatically are forced into more extensive frictional contact with the rim members, only a small part of the driving is transmitted through the thrust of the radial partitions or abutments and the slipping of the cushions on the rims is to be practically negligible both as a source of heat and of wear. However, while I have described the cushions of my wheel as interposed between abutments secured alternately to the inner and outer rim members, I do not wish to be limited to the use of a single pair of such radial partitions in connection with each cushioning element, since it might be equally desirable under some conditions to have a pair of such partitions at each end of each cushion as shown in Fig. 6. Neither do I wish to be limited to the use of spacer bushings 19 between the spokes and the dirt-excluding tubes 10, nor to other of the details herein disclosed, it being obvious that the construction might be modified in many ways without departing from the spirit of my invention.

I claim as my invention:

1. In a vehicle wheel, the combination with inner and outer rims having radially disposed projections secured alternately to the inner and outer rims and extending partly across the space therebetween, of resilient members disposed in said space and respectively abutting at their ends against consecutive projections and projecting laterally beyond one of said rims, and side flanges carried by the outer of said rims out of contact with the aforesaid rim, said flanges laterally respectively engaging the projecting portions of the resilient members.
  2. In a vehicle wheel, the combination with an inner and an outer rim, of side flanges on one of the rims radially overlapping but laterally spaced from the other rim, a central annular web on the last named rim projecting toward the rim carrying the flanges, and a pair of resilient members disposed between said rims, each of said members bearing against said web and having an integral portion projecting laterally beyond the rim having the web, said integral portion normally contacting with one of the side flanges but adapted to be moved out of its said contacting relation by a relative lateral movement of the rims in one direction.
  3. In a vehicle wheel, the combination with inner and outer rims equipped with radially disposed projections secured alternately to the inner and outer rims and extending partly across the space therebetween, of resilient members disposed in said space and respectively abutting at their ends against consecutive projections, each of said members comprising a normally rectilinear prismatic cushion having one longitudinal face thereof longer than the opposite face.
  4. In a vehicle wheel, the combination with relatively movable inner and outer rims separated by an annular space, of a plurality of radially ended resilient elements disposed in annular formation in said space and each bent from a normally rectilinear prismatic form; the outer and inner faces of each element being respectively substantially equally extended and compressed during the bending, and the outer face being normally longer than the inner face so as to compensate for the difference in the lengths of the arcs in which said faces are curved.
  5. In a vehicle wheel, the combination with relatively movable inner and outer rims, of side flanges carried by one of said
6. In a vehicle wheel, the combination with relatively movable inner and outer rims, of side flanges carried by one of said rims and radially overlapping the other thereof, cushioning elements disposed in the annular space between said rims and side flanges, said elements being arranged substantially in two rings encircling the inner rim and disposed laterally of each other, spacer means carried by one of the rims for spacing the elements comprising the two rings, and auxiliary means associated with the last named rim and the elements of each ring for preventing a relative lateral sliding thereof in one direction.
7. In a vehicle wheel, the combination with an inner rim having a central peripheral web and a pair of peripheral rings at opposite sides of said web, of an outer rim, side flanges fast upon the outer rim and extending radially inward therefrom and radially overlapping but laterally spaced from the inner rim, and resilient elements disposed in two annular formations between said rims and all normally contacting with said web, the elements of each annular formation being interlocked with one of said peripheral rings to prevent their sliding in one lateral direction upon said inner rim.
8. In a vehicle wheel, the combination with an inner and an outer rim, of an annular resilient member disposed therebetween and projecting at one side beyond the edge of one of said rims, the last named rim member being equipped with formations respectively engaging the opposite side of the resilient member and an intermediate portion of the latter for preventing a lateral movement of the resilient member with respect to said rim.

FRANCIS MEAD.
